Primary Examiner — Susan Moon Lee(74) *Attorney, Agent, or Firm* — Sughrue Mion, PLLC(57) **CLAIM**

The ornamental design for an industrial image reader, as shown and described.

DESCRIPTION

FIG. 1 is a top, front and side perspective view of an industrial image reader showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a top, front and side perspective view thereof and a cassette to be inserted into the industrial image reader.

Broken lines and portions contained within broken line are not claimed.

1 Claim, 8 Drawing Sheets(56)
